SAFETY ADAPTER FOR ELECTRICAL CONNECTORS

CROSS-REFERENCES TO RELATED APPLICATIONS

This patent application claims the benefit of provisional Application No. 62/945,018 filed Dec. 6, 2019, which is incorporated into the present disclosure by this reference.

TECHNICAL FIELD

This disclosure relates to test and measurement systems, and more particularly to connection interfaces in a test and measurement system.

BACKGROUND

Recently, applicable safety agencies have increased safety spacing requirements for electrical components. While existing equipment is generally unaffected by these new requirements, new designs for test and measurement instrumentation must meet the new requirements. One component affected by the new safety requirements are triaxial connectors. Triaxial connectors are often used in source measure units (SMUs), semiconductor test systems, as well as other test and measurement instruments.

Therefore, newly-designed high-voltage equipment using triaxial connectors must use different connectors than what had previously been the industry standard. Of course, there is a large installed base of equipment that use the previous industry-standard triaxial connectors, and those instruments are often integrated into test systems with other test fixtures and cables. Some systems, for example, may include up to 128 triaxial cables. The new-style female connectors, though, will deliberately not mate directly with the old-style male connectors because that would defeat the new safety spacing requirements.

It is important to understand the difference between functional voltage spacing requirements and safety voltage spacing requirements. While the former is determined by physics and material properties, and is aimed to prevent the dielectric breakdown within connectors, the latter is a subject for interpretation and agency regulations. Therefore, today's safe connector can become unsafe tomorrow with no physical changes, when a safety agency changes its standards.

Embodiments of the disclosed technology address shortcomings in the prior art.

DETAILED DESCRIPTION

As described herein, embodiments are directed to novel means of allowing existing cables with low-voltage triaxial connectors to safely connect to the new high-voltage triaxial connectors (up to 1100V) found on new product designs. More generally, embodiments provide a safety adapter between connections having different connector types by allowing user access to one connector at a time. Embodiments of the disclosure do not rely on a special mating interface, but instead constrain the interconnect sequence to assure safety.

FIG. 1 is a perspective view showing portions of a safety adapter assembly, according to embodiments. The safety adapter assembly is illustrated in a configuration where a first electrical connector of the safety adapter assembly is exposed and a second electrical connector of the safety adapter assembly is concealed within an example safety sleeve of the safety adapter assembly. FIG. 2 is a perspective view of the safety adapter assembly of FIG. 1, illustrating a configuration where the second electrical connector of the safety adapter assembly is exposed and the first electrical connector of the safety adapter assembly is concealed within the safety sleeve. FIG. 3 is exploded view of the safety adapter assembly of FIGS. 1-2.

As illustrated in FIGS. 1-3, a safety adapter assembly 100 may include a first electrical connector 101, second electrical connector 102, a connector body 103, and a safety sleeve 104.

The connector body 103 is configured to structurally and electrically couple the first electrical connector 101 to the second electrical connector 102. As illustrated in FIG. 3, the first electrical connector 101, the connector body 103, and the second electrical connector 102 all together have an overall connector length 105.

Each of the first electrical connector 101 and the second electrical connector 102 may be triaxial connectors, although other connector types could be used in embodiments.

The first electrical connector 101 may include a first connector type, and the second electrical connector 102 may include a second connector type that is not physically compatible with the first connector type. As used in this disclosure, "not physically compatible" means that a male connector of the first connector type could not be directly mated to a female connector of the second connector type in

normal use. Likewise, a female connector of the first connector type could not be directly mated to a male connector of the second connector type in normal use. For example, the first electrical connector 101 and the second electrical connector 102 might comply with different industry standards for connectors. As another example, the first electrical connector 101 may comply with the international standard IEC 61010, 2nd Edition, while the second electrical connector 102 may comply with the standard IEC 61010, 3rd Edition. These IEC standards are published by the International Electrotechnical Commission.

The safety sleeve 104 is preferably electrically nonconductive and configured to substantially surround the connector body 103. As used in this disclosure, "substantially surround" means largely or essentially extending around without requiring perfect encircling. The safety sleeve 104 is further configured to slidably engage the connector body 103 to selectively allow user access to the first electrical connector 101 while substantially blocking user access to the second electrical connector 102. An example of such a configuration is illustrated in FIG. 1. As used in this disclosure, "substantially blocking" means largely or essentially obstructing without requiring a perfect barricade to all access. The safety sleeve 104 is also configured to selectively allow user access to the second electrical connector 102 while substantially blocking user access to the first electrical connector 101. An example of such a configuration is illustrated in FIG. 2.

In embodiments, the safety sleeve 104 may include a longitudinal slot 106, and the safety adapter assembly 100 may include a pin 107 configured to extend away from the connector body 103 and through the slot 106 of the safety sleeve 104. The pin 107 may be, for example, a screw. The slot 106 and the pin 107 together are configured to constrain sliding movement of the safety sleeve 104 relative to the connector body 103. For example, slot 106 and the pin 107 together may limit travel of the safety sleeve 104 in a first direction 108 or in a second direction 109, or both. The first direction 108 and the second direction 109 are described more fully below in the discussion for FIG. 4. In embodiments, the pin 107 is configured to permanently join the sleeve to the connector body 103. As used in this context, "permanently join" means that the safety sleeve 104 and the pin 107 cannot be separated or moved away from each other without causing permanent damage to either component.

As illustrated in FIG. 3, the safety sleeve 104 has an overall sleeve length 1. In embodiments, the overall sleeve length 110 is not less than the overall connector length 105. In embodiments, the safety sleeve 104 is substantially cylindrical. As used in this disclosure, "substantially cylindrical" means largely or essentially cylindrical without requiring perfect cylindricality.

As illustrated in FIGS. 4-6, the safety adapter assembly 100 may be configured to serve as an adapter between a test-and-measurement cable 111 and a test-and-measurement device 112. Hence, for example, the first electrical connector 101 may be configured to connect the safety adapter assembly 100 to the test-and-measurement cable 111, and the second electrical connector 102 may be configured to connect the safety adapter assembly 100 to the test-and-measurement device 112, particularly where the test-and-measurement cable 111 has a first connector type and the test-and-measurement device 112 has a second connector type that is not physically compatible with the first connector type.

Starting with FIG. 4, FIG. 4 is a perspective view illustrating the safety adapter assembly 100 of FIGS. 1-3 con-

nected to the test-and-measurement cable in at the first electrical connector 101 of the safety adapter assembly 100, with the second electrical connector 102 of the safety adapter assembly 100 concealed within the safety sleeve 104 of the safety adapter assembly 100.

Before connecting the safety adapter assembly 100 to the connector 113 of the test-and-measurement cable 111, the user may slide the safety sleeve 104 relative to the connector body 103 (see FIG. 3) in the first direction 108 to expose the first electrical connector 101 and to conceal the second electrical connector 102 of the safety adapter assembly 100 within the safety sleeve 104. In this configuration (another example of which is illustrated in FIG. 1), the safety sleeve 104 substantially blocks user access to the second electrical connector 102, thus providing a safety feature.

The user may then attach the first electrical connector 101 to a first connector external to the safety adapter assembly 100, which, in the example illustrated in FIG. 4, is the connector 113 of the test-and-measurement cable 111.

Then, the user may slide the safety sleeve 104 relative to the connector body 103 in the second direction 109 to expose the second electrical connector 102 and to conceal the first electrical connector 101 within the safety sleeve 104.

Hence, FIG. 5 is a perspective view illustrating the safety adapter assembly 100 of FIG. 4, with the first electrical connector 101 concealed within the example safety sleeve 104 and the second electrical connector 102 exposed for connection to the test-and-measurement device 112. In this configuration (another example of which is illustrated in FIG. 2), the safety sleeve 104 substantially blocks user access to the first electrical connector 101, thus providing a safety feature.

Then, the user may attach the second electrical connector 102 to a second connector external to the safety adapter assembly 100, which, in the example illustrated in FIG. 5, is the connector 114 of the test-and-measurement device 112.

Hence, FIG. 6 is a perspective view illustrating the safety adapter assembly 100 of FIG. 5, with the second electrical connector 102 connected to the example test-and-measurement device 112.

FIG. 7 is a perspective view of the safety adapter assembly 100 of FIGS. 1-3, illustrating that, in embodiments, if the second electrical connector 102 is connected to the example test-and-measurement device 112 before the first electrical connector 101 is connected to the example test-and-measurement cable 111, the user will not be able to access the first electrical connector 101 to make the connection. Hence, as illustrated in FIG. 7, the user has connected the second electrical connector 102 to the test-and-measurement device 112 without having first connected the first electrical connector 101 to the test-and-measurement cable 111.

As illustrated in FIG. 7, though, the user may not connect the first electrical connector 101 to the test-and-measurement cable 111 after the user has connected the second electrical connector 102 to the test-and-measurement device 112. This is because the safety sleeve 104 continues to substantially block user access to the first electrical connector 101. Moreover, in some embodiments and implementations, the user cannot slide the safety sleeve 104 to expose the first electrical connector 101 because the sliding motion of the safety sleeve 104 would be limited by contact between the safety sleeve 104 and the test-and-measurement device 112, such as a panel of test-and-measurement device 112.

Accordingly, the safety adapter assembly 100 may ensure that the connections from the safety adapter assembly 100 to external connectors are made in the proper, safest sequence.

FIG. 8 is a flowchart illustrating an example method of using a safety adapter assembly for an electrical connector. As illustrated in FIG. 8, the method 800 may include sliding 801 an electrically nonconductive safety sleeve relative to a connector body of the safety adapter assembly to expose a first electrical connector of the safety adapter assembly and to conceal a second electrical connector of the safety adapter assembly within the safety sleeve; attaching 803 the first electrical connector to a first connector external to the safety adapter assembly; sliding 804 the safety sleeve relative to the connector body of the safety adapter assembly to expose the second electrical connector of the safety adapter assembly and to conceal the first electrical connector of the safety adapter assembly within the safety sleeve; and attaching 806 the second electrical connector to a second connector external to the safety adapter assembly.

The method 800 may further include constraining 802 the sliding in the first direction, for example, by using a pin coupled to the connector body and configured to extend away from the connector body and through a longitudinal slot of the safety sleeve.

The method 800 may further include constraining 803 the sliding in the second direction, for example, by using a pin coupled to the connector body and configured to extend away from the connector body and through a longitudinal slot of the safety sleeve.

The method 800 may further include permanently joining the safety sleeve to the connector body with the pin.
